UNITED STATES PATENT OFFICE.

PAUL GOSSLAR, OF NOIRAGUE, SWITZERLAND.

SHORT-CIRCUITING ROD.

Application filed November 24, 1924, Serial No. 752,074, and in Switzerland July 17, 1924. Renewed October 28, 1927.

Very often there is a need in electric lines to take off the current from the wires so that these wires may be handled without danger. This is generally done by short 5 circuiting the respective line wires and was done heretofore by means of chains or cables. These however did also endanger the lives of the operators more or less and it was proposed to use especially prepared 10 rods or poles.

It is the object of the present invention to propose a short-circuiting rod which will work surely without requiring much skill in handling and without endangering the 15 life of the operator.

The invention comprises an insulator attached to a short-circuiting rod of insulating material and two telescoping metal tubes of which the outer tube is secured removably to said insulator and carries a bracket 20 with a contact leg hinged thereto while the inner tube has a grip fastened to its outer end and adapted to take hold of a line wire, said contact leg being provided with an in- 25 interchangeable contact member and arranged so as to be swung out at a right angle from the extensible metal tube in order to make contact with a second line wire.

The annexed drawing represents one working 30 example of a short-circuiting rod according to the present invention. Fig. 1 is a side elevation showing the position of parts before contact is made. Fig. 2 is a side elevation showing the position of parts some moments after the contact has been broken 35 between the lines. Fig. 3 is a cross-section on an enlarged scale of the short-circuiting leg.

The end of a handle *a* made of an insulating substance is provided with a ribbed 40 insulator and carries a metal tube *b* which will be called the outer tube and wherein is held slidably and resiliently by means of a strong spring *d* an inner metal tube *c* having a contact-grip *e* of a well known 45 form at its outer end, which grip is adapted to afford a secure patch and contact on conductors of varying diameters. To the same tube is also affixed a clamp *f* adapted to maintain the contact leg *h* in the inoperative 50 position shown in Fig. 1. This contact leg is hinged to a horizontal bracket arm *g* to which it is also attached by means of a tension spring *i*. This spring tends to bring the leg *h* in a position perpendicular 55 to tube *b*. A small rope pulley *k* mounted

in a bracket attached to the inner tube *c* and extended through a slot to the outside of tube *b* guides a wire rope *l* which is attached at one end to the leg *h* at *h*¹ and at its other end to the end of tube *b* at *b*¹. The 60 contact leg is provided on its outer side with a contact wire *h*² extended between two small brackets and on its inner side with a grip *h*³, arranged exactly at the convenient spot where it may be seized by the clamp 65 *f* in the inoperative position of the leg.

The handling of the short-circuiting rod is in the case of two conductors as follows:

Preferably the upper of the two conductors which are to be connected together is 70 seized with the contact-grip *e*. By a pull on handle *a* the tube *c* is withdrawn from tube *b*. This operation will stretch the spring *d* and relieve grip *h*³ from clamp *f*. The rope pulley will be slid upwards and 75 the rope *l* be slackened. Spring *i* is now free to pull the leg *h* downwards, and the stronger the pull on the handle *a* the more leg *h* will follow the spring *i* and finally leg *h* will stand nearly perpendicularly to 80 rod *b* and the contact wire *h*² will come to rest on and make contact with the conductor which was to be connected to the upper conductor in order to short-circuit the two conductors. The lower conductor will be 85 touched solely by wire *h*² and therefore any sparking at the moment of short-circuiting can only take effect on wire *h*². This sparking is therefore limited to said wire which is easily replaced while all other parts of 90 the rods remain intact. The inner tube *c* may be fixed within tube *b* by giving to the handle a slight twist which will cause the small bracket of the rope pulley *k* to be caught in a recess provided within the slot 95 of tube *b*.

In the case of a three phase current where three conductors are to be connected a clamp *g*¹ which is electrically connected by metal to the bracket arm *g* is employed. The third conductor is generally located just beneath the first, and after having hooked in the first wire with grip *e* this third wire may be easily caught by said clamp while the leg *h* makes contact with the second wire 100 and then the tension of spring *d* quite alone will suffice to maintain the rod in the position of keeping the three conductors connected without need of further handling the rod. In both cases, a two phase or a three 105

phase current, the operating of the described rod will establish a short circuit between the lines which short circuit is closed in the first case through grip *e*, tube *c*, tube *d*, bracket *g*, leg *h* and contact member *h²* and in the second case the circuit is closed with the two other wires by the clamp *g¹* and all the parts mentioned for the second case.

In Fig. 3 is shown in a cross-section a modified form and arrangement of the contact member of leg *h*. Instead of a wire *h²* a bar *s* of carbon or of an equivalent substance is dove-tailed within a slot of leg *h*.

Having now fully described my invention what I claim is:

1. In a short-circuiting rod and in combination a first slotted tube having a bracket standing off sideways; a second tube arranged slidably within the first and resiliently attached thereto; a contact grip at the end of said second tube; a leg hinged to said bracket and carrying a contact member; a tension spring attached to said bracket and said leg and adapted to establish the operative position of the leg; a grip provided on the leg and a clamp on the second tube and adapted to hold the leg by said grip in its inoperative position substantially as shown and described.
2. In a short-circuiting rod and in combination a first slotted tube having a bracket standing off sideways; a second tube arranged slidably within the first and resiliently attached thereto; a contact grip at the end of said second tube; a leg hinged to said bracket and carrying a contact member; a tension spring attached to said bracket and said leg and adapted to establish the operative position of the leg; a small bracket carrying

a rope pulley mounted on the second tube and extended through the slotted part of the first tube and a rope attached to the first tube and the leg and guided by said rope pulley so as to regulate the deflection of the leg according to the withdrawal of the second from the first tube substantially as shown and described.

3. In a short-circuiting rod and in combination a first slotted tube having a bracket standing off sideways; a second tube arranged slidably within the first and resiliently attached thereto; a contact grip at the end of said second tube; a leg hinged to said bracket and carrying a contact member; and a second contact grip provided on the first tube on the opposite side to that where the leg is hinged to, all substantially as shown and described.

4. In a short-circuiting rod and in combination an insulated handle; a first slotted tube fixed thereto and having a bracket standing off sideways; a second tube arranged slidably within the first and resiliently attached thereto; a contact grip on the second tube, a leg hinged to said bracket and carrying a contact member; a second contact grip on the first tube opposite to where the leg is hinged to it; a tension spring attached to said bracket and said leg and adapted to establish the operative position of said leg; means for controlling the deflection of the leg according to the withdrawal of the second from the first tube and means for securing the leg in its inoperative position, substantially as shown and described.

In testimony whereof I affix my signature.

PAUL GOSSLAR.
